(57) **CLAIM**

The ornamental design for an actuator, as shown and described.

DESCRIPTION

FIG. 1 is a perspective view of an actuator in accordance with our new design;

FIG. 2 is a top plan view thereof;

FIG. 3 is a right side elevational view thereof; the left side elevational view being a mirror image thereof;

FIG. 4 is a front elevational view thereof; and,

FIG. 5 is a rear elevational view thereof.

The broken lines in the Figures are for illustrative purposes only and form no part of the claimed design.
